CLAIM

The ornamental design for a floor lamp, as shown and described.

DESCRIPTION

FIG. 1 is a perspective view of a floor lamp showing the new design;

FIG. 2 is another perspective view thereof;

FIG. 3 is yet another perspective view thereof;

FIG. 4 is a left view thereof;

FIG. 5 is a right view thereof;

FIG. 6 is a rear elevation view thereof;

FIG. 7 is a front elevation view thereof;

FIG. 8 is a top plan view thereof;

FIG. 9 is a bottom plan view thereof; and,

FIG. 10 is an enlarged detail view of area 10 in FIG. 7. Portions of the floor lamp depicted with dashed lines form no part of the claim design. The broken lines surrounding the area of the detail in FIG. 7 and surrounding FIG. 10 denote the boundary of the enlarged detail view and form no part of the claimed design.
